UNITED STATES PATENT OFFICE

2,079,522

VEHICLE WINDOW SILENCER

Oscar J. Mortensen, Superior, Wis.

Application December 30, 1935, Serial No. 56,768

1 Claim. (Cl. 292—79)

This invention relates to a vehicle window silencer, and has for the primary object the provision of a device of this character which may be readily adapted to a vehicle window without the use of screws or like fasteners and which will place a desired pressure on the glass panel of a window to prevent rattling and which will permit the panel to slide freely to either open or close the window.

With these and other objects in view, this invention consists in certain novel features of construction, combination and arrangement of parts to be hereinafter more fully described and claimed.

For a complete understanding of my invention, reference is to be had to the following description and accompanying drawing, in which—

Figure 1 is a fragmentary sectional view showing my invention adapted to a window wherein the latter is provided with a molding.

Figure 2 is a view similar to Figure 1, showing my invention adapted to a window wherein the latter has a comparatively wide molding.

Figure 3 is a side elevation illustrating the silencer.

Figure 4 is a top plan view illustrating the same. Referring in detail to the drawing, the numeral 1 indicates a fragmentary portion of a window frame and of the type employed in motor vehicle construction and which slidably supports a glass panel 2. Frequently, the panel of a window frame of this character comes loose and creates excessive noise and to cure this objection my invention may be readily adapted to the window frame and bear against the panel with sufficient force to prevent the panel from moving by vibration or the like.

A base plate 3 has formed upon one end a leg 4 extending at approximately right angles to the plate 3 and has its free end curved, as shown at 5. The leg 4 is adapted to contact a molding 6 of the window frame 1 with the plate resting upon the sill of the window frame. The plate 3 has its edges formed with extensions which are bent over but spaced from said plate to provide guides 7 for a slidable plate 8. The plate 8 has its outer end slotted longitudinally at two spaced intervals and the metal bounded by the slits is bent in opposite angular directions to provide a pair of outer gripping fingers 10 which are directed at

an angle toward the leg 4, and a central ear 9. The fingers 10 are directed toward and are designed to have their ends contact with the glass panel guide, as shown in Figures 1 and 2, and is held tightly against one wall of the panel guide 5 by a coil spring 11. The coil spring 11 has one end connected to the ear 9, while the opposite end is connected to an arm 14 by a pin 13 or some other means (not shown). The arm 14 is arcuately curved and preferably constructed from 10 channel iron and has one end pivoted to ears 15, as shown at 16. The ears form an integral part of the plate 3 and the other end of the arm is bifurcated to form spaced ears 17 and journaled to said ears 17 is a roller 18 contacting the panel 15 2 with desired force to prevent the panel from rattling in its guide. The arrangement of the plates 3 and 8 and the spring 11 permits this device to be readily adjusted and adapted to window frames of different sizes. When a window frame 20 has a comparatively wide molding, as shown at 19, in Figure 2, a cushion strip 20 is provided contacting the molding and provided with a beading 21 engaged by the leg 4.

A device of the character described will efficiently prevent rattling of a window panel and may be readily adapted to the window frame and to window frames of different sizes without the employment of detachable fasteners or the use of tools for the installation.

Having described the invention, I claim:

A device for preventing vibration of a panel when moved on a frame, comprising a plate having one end bent at an angle and having its sides rebent to form guideways arranged over the plate 35 and having ears between the guideways and the angle end thereof, a second and slidable plate movable in the guideways and having its outer end formed with angle fingers directed toward the angle end of the first named plate and an opposite directed ear between said fingers, an arcuate arm pivoted to the ears of the first named plate and extending thereover in the direction of the finger and ear carrying end of the second and slidable plate, an anti-friction roller journaled on 45 the free end of the arm and a coiled compression spring connected to the arm and to the ear of the slidable plate.
